UNITED STATES PATENT OFFICE.

EDWARD F. KUNATH, OF JERSEY CITY, NEW JERSEY, ASSIGNOR TO UNDERWOOD TYPE-WRITER COMPANY, OF NEW YORK, N. Y., A CORPORATION OF NEW JERSEY.

TYPE-WRITING MACHINE.

952,203.

Specification of Letters Patent. Patented Mar. 15, 1910.

Application filed July 29, 1905. Serial No. 271,763.

To all whom it may concern:

Be it known that I, EDWARD F. KUNATH, a citizen of the United States, residing in Jersey City, in the county of Hudson and State of New Jersey, have invented certain new and useful Improvements in Type-Writing Machines, of which the following is a specification.

This invention relates to the paper-feeding devices of typewriting machines, and its object is to facilitate the production of carbon or duplicate copies of an original type-written sheet, and particularly to provide means for making a carbon record, tally or duplicate of the prices or amounts entered upon a succession of bills or invoices.

In the preferred form of my invention, I employ an endless band of carbon paper or ribbon, inked only on one side. This endless band is passed around the platen, with the inked side toward the latter; and I provide means to coöperate with the platen for carrying said band and causing the latter to feed around the platen.

In the illustrated form of the invention, I provide two rolls remote from the platen, over which said endless band is carried; and between said rolls and the platen, I mount a pair of paper reels, one to wind and the other to pay out the paper, the latter being led from the delivery reel or spool down and around the platen within the inking band, and then up from the platen to the winding reel. The platen, spools and paper are all confined within the endless inking band. The machine being thus equipped, a bill is introduced around the platen in the usual manner, with the price or amount columns on the bill overlying the inking band and record web; and then the bill is written as usual. Such prices and amounts as are written on the bill are duplicated by the said endless inking band upon the paper web, so that at the end of the day a complete record or tally is obtained on the single tally strip of all of the transactions which have been typewritten during the day upon a large number of bills.

In the accompanying drawings, Figure 1 is a perspective view of one form of my improvements as applied to the well known "Underwood" typewriting machine. Fig. 2 is a detail of a paper reel. Fig. 3 shows a fixed axle whereon the winding paper reel is detachably mounted. Fig. 4 illustrates de-

tails for detachably connecting the paper reel to its fixed axle.

Upon the front side of a cylindrical platen 1, revolutely mounted in a platen frame 2 and rotated by means of a hand wheel 3 or otherwise, strike types 4, carried upon type bars 5, which are operated by finger-keys in the usual manner.

Passing around one end of the platen, preferably the right-hand end, is an endless band 6, inked as at 7 only upon its under or inner side, that is, the side next to the platen. Said band is of suitable length, and its upper end runs over a pair of idle rolls or guide pulleys 8. The longitudinal movements of the band are effected by the rotation of the platen, with which coöperates a set of pressure rolls, one whereof is seen at 9; said rolls being pressed against the platen by springs 10, and released at will by a finger lever 11 connected by a link 12 to a crank arm 13 formed upon a releasing shaft 14. The rolls 8 preferably of soft rubber, are loosely mounted upon studs 15 carried upon the upper end of a standard 16, which is fixed at its base to the right-hand end of the platen frame 2 and inclines upwardly and rearwardly therefrom. Flanges 15^a for guiding the band are fixed upon the studs by means of hubs 15^b. A strip of record paper 17 is wound upon a delivery spool 18 and led thence downwardly and around the platen within the inking band 6, and then upwardly to a winding spool 19; so that during the rotation of the platen the paper may pay off the spool 18 and pass down around the platen and there be written upon and then up to become wound on the spool 19. Said spools, which are supported upon the standard 16, it will be seen are within the inking band 6, and between the idle rolls 8 and the platen; the winding spool being above the delivery spool.

The paper is drawn off from the delivery spool by the rotation of the platen; said paper being pressed against the platen by the pressure roll 9. In order to enable the winding spool 19 always to take up the paper strip as fast as the latter is delivered from the platen, I connect the platen by an endless cord 20 to a pulley 21, loose upon fixed axle or stud 24 and connected to the winding reel or spool 19; said cord fitting in a groove 22 formed in the periphery of the platen. The diameter of the pulley 21

is only about one-third of the diameter of the platen, so that the spool 19 tends to make three revolutions to one revolution of the platen. This tendency does not however 5 result in a rupture of the paper strip, since the cord 20 may readily slip around the pulley 21 when the paper delivered from the platen becomes taut, the result being that the paper is wound smoothly and tightly 10 upon the spool 19.

The spools or reels 18, 19 may be readily slipped off from their fixed axles 23, 24; each spool being provided with a spring latch 25, secured upon the outside of the spool hub 15 26 and projecting within a slot 27 formed transversely through the wall of the hub. Said spring detent is adapted to engage a peripheral groove 28 formed in the fixed spool axle. The pulley 21 is provided with 20 a pin 29 to engage a recess 30 in the hub of the spool 19, to cause the spool to rotate with the pulley; and this spool is also provided with a paper hook 31 upon its core.

In operation, the inking band being suitably mounted, a full paper reel 18 is slipped upon the fixed axle or stud 23, and the leading edge of the paper is carried first down from the spool and around the platen within the inking band 6, and then upwardly, 30 and is caught upon the hook 31 upon the hub of spool 19. Then a bill or other sheet 32 is introduced around the body of the platen in the usual manner and written upon the tally strip devices being placed 35 forward of the introductory side of the machine or in front of the usual paper shelf (forming part of frame 2) to give clearance to permit the main sheet or bill to overlap the tally strip; and such figures or characters as are written upon the right-hand edge 40 portion of the bill are duplicated by means of the inking band 6, upon the tally strip 17. It will be seen that as soon as one bill is finished it may be readily withdrawn without 45 rotating the platen, since a depression of the release key 11 throws off the pressure rolls 9, to permit the withdrawal of said bill, without however disturbing either the feeding band or the record web. Then a new 50 bill may be inserted and written, and so on until the web, which during the rotation of the platen winds upon spool 19, is exhausted. Then the spools may be withdrawn and fresh ones having a new web may be substituted. The platen is advanced line by line in the usual manner.

Variations may be resorted to within the scope of my invention, and portions of my improvements may be used without others.

60 Having thus described my invention, I claim:

1. In a typewriting machine, the combination with a traveling platen frame, of a bracket or support erected upon said platen frame, a tally-strip delivery spool and a

tally-strip feeding spool both mounted in permanent positions upon said bracket or support, the strip passing from the delivery spool around the platen and thence to the winding spool, all of the tally-strip devices 70 being permanently located wholly to one side of the main body of the platen, to leave said main body free for the feeding of successive main sheets or bills around the same, mechanism operating upon said winding spool to 75 wind the same, and means independent of the recited tally-strip devices, to coöperate with the main body of the platen to feed said main bills or sheets; said feeding means being releasable to permit the main sheets to 80 be inserted and withdrawn while the tally strip remains stationary.

2. In a typewriting machine, the combination with a traveling platen frame, of a bracket or support erected upon said platen frame, a tally-strip delivery spool and a tally-strip feeding spool both mounted in permanent positions upon said bracket or support, the strip passing from the delivery spool around the platen and thence to the 85 winding spool, all of the tally-strip devices being permanently located wholly to one side of the main body of the platen, to leave said main body free for the feeding of successive main sheets or bills around the same, 90 mechanism operating upon said winding spool to wind the same, an endless band or loop of inking material carried around said platen, and supports on said bracket for said loop, said tally-strip spools and 95 tally-strip being mounted wholly within said loop, and means independent of the recited tally-strip devices to coöperate with the main body of the platen to feed said main bills or sheets; said feeding means being releasable to permit the main sheets to be 100 inserted and withdrawn while the tally strip remains stationary.

3. In a typewriting machine, the combination with a traveling platen frame, of a bracket or support erected upon said platen frame, a tally-strip delivery spool and a tally-strip feeding spool both mounted in permanent positions upon said bracket or support, the strip passing from the delivery 110 spool around the platen and thence to the winding spool, all of the tally-strip devices being permanently located wholly to one side of the main body of the platen, to leave said main body free for the feeding of successive main sheets or bills around the same, mechanism operating upon said winding spool to wind the same, an endless band or loop of inking material carried around said platen, and supports on said bracket for said 115 loop, said tally-strip spool and tally-strip being mounted wholly within said loop; all of the foregoing tally-strip and inking devices being mounted forward of the introductory side of the platen, to leave a clear- 120 125 130

- ance to permit the main sheet or bill to overlap the tally-strip and inking band, and means independent of the recited tally-strip devices to coöperate with the main body of the platen to feed said main bills or sheets; said feeding means being releasable to permit the main sheets to be inserted and withdrawn while the tally-strip remains stationary.
- 10 4. In a typewriting machine, the combination with a traveling platen frame, of a bracket or support erected upon said platen frame, a tally-strip delivery spool and a tally-strip feeding spool both mounted in permanent positions upon said bracket or support, the strip passing from the delivery spool around the platen and thence to the winding spool, all of the tally-strip devices being permanently located wholly to one side of the main body of the platen, to leave said main body free for the feeding of successive main sheets or bills around the same, mechanism operating upon said winding spool to wind the same; all of the foregoing tally-strip and inking devices being mounted forward of the introductory side of the platen, to leave a clearance to permit the main sheet or bill to overlap the tally strip, and means independent of the recited tally-strip devices, to coöperate with the main body of the platen to feed said main bills or sheets; said feeding means being releasable to permit the main sheets to be inserted and withdrawn while the tally-strip remains stationary.
- 15 5. In a typewriting machine, the combination with a traveling platen frame, of a bracket or support erected upon said platen frame, a tally-strip delivery spool and a tally-strip feeding spool both mounted in permanent positions upon said bracket or support, the strip passing from the delivery spool around the platen and thence to the winding spool, all of the tally-strip devices being permanently located wholly to one side of the main body of the platen, to leave said main body free for the feeding of successive main sheets or bills around the same, mechanism operating upon said winding spool to wind the same, means also being provided on said support to carry a carbon strip in position to cover that portion of the tally strip which encircles the platen, and means independent of the recited tally-strip devices to coöperate with the main body of the platen to feed said main bills or sheets; said feeding means being releasable to permit the main sheets to be inserted and withdrawn while the tally strip remains stationary.
- 20 6. In a typewriting machine, the combination with a traveling platen frame, of a bracket or support erected upon said platen frame, a tally-strip delivery spool and a tally-strip feeding spool both mounted in permanent positions upon said bracket or support, the strip passing from the delivery spool around the platen and thence to the winding spool, all of the tally-strip devices being permanently located wholly to one side of the main body of the platen, to leave said main body free for the feeding of successive main sheets or bills around the same, mechanism operating upon said winding spool to wind the same, means also being provided on said support to carry a carbon strip in position to cover that portion of the tally strip which encircles the platen, and means independent of the recited tally-strip devices to coöperate with the main body of the platen to feed said main bills or sheets; said feeding means being releasable to permit the main sheets to be inserted and withdrawn while the tally strip remains stationary.
